BOAT

Rudolph W. Miller, Brooklyn, N. Y.

Application February 2, 1934, Serial No. 709,397

1 Claim. (Cl. 115—39)

This invention relates to boats, and an object is to provide an improved construction and arrangement of power driven propelling mechanism for boats of any size from toys to full sized 5 craft.

This and other objects which will be apparent to those skilled in this particular art are accomplished by means of the invention illustrated in the accompanying drawing, in which,

10 Fig. 1 is a diagrammatic plan view illustrative of one embodiment of this invention;

Fig. 2 is a diagrammatic side elevation of the features shown in Fig. 1; and

15 Fig. 3 is an end elevation of the stern of the boat illustrated in Figs. 1 and 2.

As illustrated in the accompanying drawing, the invention is shown in connection with a hull 5 of any standard form of construction. Any suitable source of power 6 such as an internal combustion engine, or the like, is adapted to drive the usual propeller 7 secured to a propeller shaft 8 which is driven through a suitable transmission 9.

On each side of the hull 5 a casing 10 is mounted 25 preferably at about the level of the water line or slightly below, and the casing may extend downwardly along the sides of the hull to any desired extent. The casing 10 is arranged so as to provide a water passage 11 having a water intake

30 opening 12 at the forward end of each passage on opposite sides of the hull. The passages 11 extend rearwardly around the stern of the hull where they converge upon the propeller 7 and the casing is so arranged that a discharge passage 35 13 surrounds the propeller 7 and forms in effect a continuation of the passages 11 so that the propeller 7 is effective upon water flowing rearwardly through the passages 11 and drives the same outwardly through the discharge outlet 13.

In the illustrated embodiment of the invention, an auxiliary propeller 14 is located in each water passage 11 forward of the propeller 7. The auxiliary propeller shafts 15 are driven from the 40 transmission 9. The effect of the auxiliary

propellers is to draw water through the passage 11 and drive it with considerable force to the propeller 7 in the discharge outlet 13.

It will be noted that the casing 10, as illustrated, extends considerably to the rear of the hull 5 and constitutes an additional load overhanging the stern. In order to prevent this load from increasing the draft of the hull, an airtight tank 16 is formed across the upper portion 10 of the extended casing to increase the buoyancy 10 thereof.

In operation, water is drawn into the passageways 11 on each side of the hull and is forced rearwardly by the propellers 14 to the propeller 7 which discharges it through the discharge outlet 13. The size and length of the passages 11 can be varied and the arrangement of propellers can also be changed or modified in any practicable manner. Suitable valves, not shown, may obviously be employed to shut water out of the passages 11 and 13 when repairs are necessary, and grilles 17 or the like will be suitable at the inlets 12 to prevent extraneous materials, such as wood or the like, from entering the passages and damaging the propellers or other parts.

It will be apparent that the invention can be variously modified or adapted within the scope of the appended claim.

I claim:

The combination with a boat hull and a conventionally arranged propeller of a casing located outside of said hull and cooperating with the outer face of said hull to form a compartment enclosing the said propeller and providing a discharge outlet astern of said propeller and a water-containing chamber forward of said propeller, inlets to said compartments on opposite sides of said hull, and means for forcing water from said inlets into said chamber so as to maintain a pressure of water in said chamber against said propeller to permit effective operation of said propeller at high speed and prevent the formation of a vacuum thereby.
